(57) **CLAIM**

The ornamental design for cable management fingers, as shown and described.

DESCRIPTION

FIG. 1 is a front left side perspective view of an ornamental design for cable management fingers.

FIG. 2 is a left side view of the cable management fingers of FIG. 1.

FIG. 3 is a rear left side perspective view of the cable management fingers of FIG. 1.

FIG. 4 is a rear view of the cable management fingers of FIG. 1.

FIG. 5 is a front right side perspective view of the cable management fingers of FIG. 1.

FIG. 6 is a right side view of the cable management fingers of FIG. 1.

FIG. 7 is a top view of the cable management fingers of FIG. 1; and,

FIG. 8 is a bottom view of the cable management fingers of FIG. 1.

1 Claim, 8 Drawing Sheets
